(57) **CLAIM**

The ornamental design for a trim bead for a building wall, as shown and described.

DESCRIPTION

FIG. 1 is a rear view of the trim bead for a building wall. FIG. 2 is a right side view of the trim bead for a building wall. FIG. 3 is a left side view of the trim bead for a building wall. FIG. 4 is a front view of the trim bead for a building wall. FIG. 5 is a top plan view of the trim bead for a building wall. FIG. 6 is a bottom plan view of the trim bead for a building wall. FIG. 7 is a top perspective view of the trim bead for a building wall; and, FIG. 8 is a bottom perspective view of the trim bead for a building wall. The broken lines are for illustrative purposes only and form no part of the claimed design.
